UNITED STATES PATENT OFFICE.

CHESTER A. ANDERSON, OF COMMERCE, TEXAS.

CLOTHES-LINE.

1,281,475.

Specification of Letters Patent. Patented Oct. 15, 1918.

Application filed April 12, 1918. Serial No. 228,199.

To all whom it may concern:

Be it known that I, CHESTER A. ANDERSON, a citizen of the United States, residing at Commerce, in the county of Hunt, State 5 of Texas, have invented a new and useful Clothes-Line; and I do hereby declare the following to be a full, clear, and exact description of the invention, such as will enable others skilled in the art to which it app- 10 pertains to make and use the same.

The present invention relates to a clothes line, and has for its object to provide a device of this character which embodies novel features of construction whereby an endless 15 line or cable is mounted upon guide pulleys and arranged so that different portions thereof can be readily moved toward or away from one end of the device, thereby facilitating the placing of clothes upon the 20 line and the removal of clothes therefrom.

Further objects of the invention are to provide a device of this character which is comparatively simple and inexpensive in its construction, which can be readily mounted 25 in a yard or upon a roof and will tend to conserve space, which can be readily adjusted to remove slack and keep the line taut, and which can be quickly taken apart 30 to make any necessary repairs or adjust- ment.

With these and other objects in view, the invention consists in certain novel combinations and arrangements of the parts as will 35 more fully appear as the description pro- ceeds, the novel features thereof being pointed out in the appended claims.

For a full understanding of the invention, reference is to be had to the following description and accompanying drawings, in 40 which:—

Figure 1 is a top plan view of a clothes line device constructed in accordance with the invention, portions being broken away.

Fig. 2 is a horizontal sectional view on the line 2—2 of Fig. 1, looking in the direction of the arrows.

Fig. 3 is an enlarged transverse sectional view on the line 3—3 of Fig. 1.

Fig. 4 is a plan view of one of the end 50 frames with the top strip swung upwardly to show the guide pulleys.

Fig. 5 is a similar view of the other end frame.

Fig. 6 is a longitudinal sectional view 55 through the end frame which is remote from the operating wheel.

Fig. 7 is a similar view through the other end frame, being taken on the line 7—7 of Fig. 1.

Corresponding and like parts are referred 60 to in the following description and indicated in all the views of the drawings by the same reference characters.

Referring to the drawings, the numeral 1 designates an endless clothes line which is 65 threaded back and forth around guide pulleys upon a pair of similar and complementary end frames A and B. These frames are horizontally disposed and each include a pair of spaced strips between which a 70 number of guide pulleys are mounted. The end frame A is provided with four guide pulleys 2 which are arranged in groups of two each, while the end frame B is provided with a large drive pulley 3 and a pair 75 of guide pulleys 4, the latter being of substantially the same size as the pulleys 2, and being arranged on opposite sides of the drive pulley 3. The endless clothes line 1 is looped around the large drive pulley 3, 80 extending from opposite sides thereof to the corresponding pairs of guide pulleys 2. The two reaches of the cable are carried around the respective pairs of guide pulleys 2 and then brought back to the end frame 85 B and passed around the guide pulleys 4, the connecting portion of the line extending between the guide pulleys 4 at the rear of the drive pulley 3. The end frame A is intended to be adjustably secured to suitable 90 supports such as the posts 5, while the end frame B may be rigidly secured to a suitable support such as the rail 6. A crank handle 7 is provided for turning the drive pulley 3, and it will be obvious that when this drive 95 pulley is manipulated the different reaches of the endless clothes line will be caused to move back and forth between the two end frames A and B, thereby facilitating the operation of placing clothes upon the line 100 and removing them therefrom.

A clevis 8 is connected to each end of the frame A by means of a removable bolt 9, and a cable 10 is connected to each clevis, said cables being shown as extending around 105 guide pulleys 11 on the posts 5, and as connected to a turn buckle 12. If desired, the ends of the cables 10 may be knotted at 13 so as to be adjustably engaged by hooks 14 at the ends of the turn buckle. With this 110 construction it will be obvious that any slack in the clothes line can be readily taken up

by properly adjusting the turn buckle and the connection between the turn buckle and the knotted ends of the cables.

The end frame B comprises a lower strip 15, and an upper strip 16, with spacing blocks 17 interposed between the ends of the strips. The upper strip 16 may be hingedly connected at one end, as indicated at 18, and detachably secured at the opposite end by screws 19. The spindles 20 for the pulleys 4 have the ends thereof loosely received within recesses 21 in the two strips of the frame, so that when the strips are held in normal position the spindles and pulleys are retained in normal position, although the spindles and pulleys are removable when the upper strip 16 is swung upwardly, as indicated by Fig. 4. The large drive pulley 3 is mounted upon an enlarged polygonal portion 22^a of a shaft 23, said shaft extending upwardly through an opening in the upper strip 15 and having the crank handle 7 applied thereto.

The opposite end frame A has a somewhat similar construction, being composed of a lower strip 24, an upper strip 25, and spacing blocks 26. The upper strip 25 is hingedly connected at one end, as indicated at 27, being normally held in position by removable fastening members such as the screws 28. Openings 29 are provided in the opposite ends of the frame A to receive the bolts 9 of the clevises 8, and preparatory to swinging the upper strip 25 upwardly it is necessary to remove these bolts 9 as well as the screws 28. The pulleys 2 are loose upon spindles 30 which have the ends thereof received within recesses 31 in the strips 24 and 25, the pulleys and spindles being held securely in position when the frame is closed, although they are both removable when the strip 25 is released and swung upwardly, as indicated by Fig. 5. In Figs. 6 and 7 the upper strips of the two frames are also indicated by dotted lines as partially swung upwardly.

The end frame A is provided with guide eyes 32 which engage the outside reaches of the clothes line and prevent the possibility of clothes thereon being injured by being carried into the frame and around the guide pulleys. These guide eyes are preferably secured, as indicated at 33, to the lower strip 24 of the frame, so that they do not interfere in any manner with opening up the frame when it is desired to obtain access to the pulleys therein.

Having thus described the invention, what I claim as new and desire to secure by Letters Patent, is:

1. A clothes line including two similar and opposed end frames arranged horizontally and in a parallel relation to each other, each of the end frames being formed of

spaced strips, two pair of guide pulleys 65 journaled between the spaced strips of one end frame, a large drive pulley journaled between the spaced strips of the other end frame at the middle thereof, guide pulleys mounted upon the second end frame at the 70 ends thereof, an endless clothes line threaded around the main drive pulley and the two pair of guide pulleys and the end pulleys, and means for turning the main drive wheel to move the different portions of the line 75 back and forth between the end frames.

2. A clothes line including two similar and opposed end frames arranged horizontally and in a parallel relation, guide pulleys mounted upon the end frames, a clothes 80 line threaded around the guide pulleys and extending back and forth between the end frames, cables connected to the ends of one of the end frames and provided with a series of knotted portions, fixedly supported 85 guide members engaging the cables, and a turn buckle having hooked ends adjustably engaging the knotted portions of the cables to adjust the position of the end frame and hold the clothes line taut. 90

3. A clothes line including two similar and opposed end frames arranged horizontally and in a parallel relation, each of the end frames being formed with spaced strips having corresponding recesses in the inner 95 faces thereof, one of the spaced strips being hingedly mounted, spindles extending between the strips and having the extremities thereof extending between the recesses, pulleys mounted upon the spindles, an endless 100 clothes line threaded around the pulleys and extending back and forth between the end frames, and means for moving the clothes line.

4. A clothes line including two similar 105 and opposed end frames arranged horizontally and in a parallel relation, each of the end frames being formed of spaced strips having corresponding recesses in the inner faces thereof, one of the strips of each frame 110 being hingedly mounted so as to be swung outwardly when released, spindles extending between the strips of each frame and having the ends thereof received within the before mentioned recesses, pulleys mounted upon 115 the said spindles, a clothes line threaded around the pulleys and extending back and forth between the end frames, guide members upon one of the end frames loosely receiving the clothes line to prevent the clothes from 120 being carried into the frame and around the guide pulleys, and a large drive pulley mounted upon the opposite end frame and engaging a portion of the clothes line for moving it back and forth around the pulleys. 125

5. A clothes line including two similar and opposed end frames arranged horizontally and in a parallel relation, each of the end

frames being formed with spaced strips, two pair of guide pulleys journaled between the spaced strips of one end frame, a large drive pulley mounted between the spaced strips of the other end frame at the middle thereof, guide pulleys journaled upon the second end frame at the ends thereof, an endless clothes line threaded around the main drive pulley and the two pair of guide pulleys and the end guide pulleys, and guide eyes applied to the first mentioned frame and loosely

receiving portions of the clothes line to prevent the clothes from being carried into the frame and around the pulleys.

In testimony whereof I have signed my name to this specification in the presence of two subscribing witnesses.

CHESTER A. ANDERSON.
